7 Claims. (Cl. 179—90)

1

The present invention relates to a number indicator in trunk call stations operating with selector dials, and particularly telephone stations, where number rollers are worked in conjunction with the numbers dialed by means of an electromagnet under the influence of the dialing current impulses, with the help of pawls and ratchets, of which one is allotted to each number roller in such a way that each number can be read off immediately after dialing. The invention consists in an arrangement whereby, for the switching over of the current from one number roller to the next, a second electromagnet which serves as commutation magnet is provided, which comes into action at the close of a series of impulses and operating control-wheels, one of which in each case brings the pawl allotted to the number roller to be dialed into gear with the corresponding ratchet, whilst the other pawls allotted to the number rollers which are not to be dialed are raised by the corresponding ratchets. The control wheels are so arranged that all pawls come into action one after the other. Each pawl has a special control wheel which contains a hollow intended to receive a pin connected with the pawl, the pawl being brought into gear with the corresponding ratchet, when the pin is laid in the hollow, and being raised by the ratchet and thus put out of action when the pin is laid on the ratchet rim. All control wheels are set on a shaft which is driven by the commutation magnet with the help of a pawl and a ratchet, and are arranged in such a way that the hollows are displaced by each other, whereby at the same time only the pin which is in contact with the pawl of the particular number roller to be dialed can enter the hollow, so that only one pawl comes into action at one time. The exciting coil of the transmission magnet for the number rollers is connected up with a circuit which is sporadically interrupted by the impulse contact of the number switch in such a way that it is subject to the influence of the dialing current impulses. The exciting coil of the commutation magnet lies in a circuit under the influence of the short circuit contact of the number switch, so that it always comes into action at the close of a series of impulses and causes the drive to be switched over from one number roller to the next.

The circuit of the commutation magnet is best interrupted when the number indicator is at rest by a closed circuit working contact under the influence of the first number roller, which is so arranged that the commutation magnet can

2

only receive current when the first number roller has turned by at least one division. In one specific embodiment of the invention, the reversal of number rollers and control wheels can be effected simultaneously by means of a reverse key. Means can also be installed to achieve this reversal automatically on hanging up or replacing the receiver. For this purpose, a reversal magnet is provided, the exciting coil of which is connected with a circuit under the influence of the hook commutation switch. It is advisable to arrange, parallel to the working side of the hook commutation contact serving to close the station loop, a working contact which is dependent upon the control wheels and which maintains the loop circuit for the reversal magnet until the reversal of the number rollers and control wheels is completed.

Two specific embodiments of the number indicator for telephone connections constituting the present invention are described below with reference to the accompanying drawings:

Fig. 1 is a longitudinal section of the number indicator,

Fig. 2 represents the commutation mechanism for the control wheels,

Fig. 3 shows the reversal mechanism of these control wheels,

Fig. 4 shows the connection of the electromagnets with various control organs,

Fig. 5 is a view of the control wheels,

Fig. 6 shows the arrangement of the number rollers,

Fig. 7 is a switch arrangement of a telephone station with a number indicator according to the invention, the reversal being carried out by hand,

Fig. 8 is a switch arrangement of a station with an automatically reversing number indicator.

Both types of construction differ only in so far as the one is equipped for reversal by hand and the other for automatic reversal. They are therefore similar in the essential points and described together.

The organs of the dialing, commutation and reversal mechanism are arranged between two side-plates 1 held together by separation column 2 and enclosed in a frame 3—shown only in part—with windows 4. Number rollers 6, of which there are in this particular case nine, being adapted to the longest number to be dialed, are mounted on a common shaft 7 so that they can revolve freely, and are provided for dialing purposes with one ratchet 8 each and for re-

versal purposes with a heart-shaped lug 9. Ratchet 8 is adapted to be engaged by a pawl 10 and a stop-pawl 11. All pawls 10 are rotatably mounted on a common bar 12, which in its turn is fixed to a U-shaped transmission bar 13 (Figs. 1 and 2). Transmission bar 13 is connected by means of a strap 14 with armature 15 of an electromagnet 16 serving as transmission magnet and said transmission bar 13 is rotatably mounted on shaft 17, the ends of which are let into side-plates 1. All pawls 10 are therefore set in motion simultaneously by armature 15. Each pawl possesses a longitudinal opening which receives a pin 20 fixed in a guide hoop 19. In the same guide hoop 19 a further pin 21 is provided which either moves into a hollow 23 in a control wheel 22 or rests on its rim according to whether the pawl 10 is to be brought into or out of gear with ratchet 8. In Fig. 1 pawl 10 is in gear with ratchet 8. Guide hoop 19 has horseshoe-shaped parts connecting it with the hub of control wheel 22. Moreover a hole is bored in the bridge of the hoop into which a pin screw 25 screwed into a guide rail 24 projects, which also serves to guide hoop 19. To each pawl is allotted one of these guide hoops 19 with pins 20 and 21 and one control wheel 22 as can be seen from Fig. 1. All control wheels are set on a common shaft 26 fixed in side-plates 1 which likewise carries a ratchet 27 (Fig. 2). Control wheels 22 are so arranged that hollows 23 are adjusted towards each other. In this way one pin 21 lies at one time in a hollow, i. e. only one pawl 10 is in gear with the corresponding ratchet. A pawl 28 works in conjunction with ratchet 27 (Fig. 2), this being fixed on a rotating commutation hoop 29 on shaft 17. The longitudinal part 29' of this hoop has an arm 29'' (Fig. 4), which is connected by means of a strap 30 with the armature 31 of an electromagnet 32 serving as commutation magnet. Two bars 33, of which only one is to be seen in Fig. 3, are rigidly connected with commutation hoop 29 by means of screw springs 34 and are arranged one on each side of the apparatus. At their upper ends these bars 33 contain longitudinal holes 35, through which a lever rod 36 extending under all pawls 10 protrudes. This is best let into the longitudinal holes in side-plates 1 which are similar to those of bars 33. A reversal hoop 37, which is very well seen in Fig. 4, is rotatably mounted on shaft 17 and serves to reverse both number rollers 6 and control wheels 22. Rigidly connected to this reversal hoop by means of two further screw springs 38 are two release bars 39, similar to release bars 33, the upper ends of which are pierced by lever rod 36 which fits into the longitudinal holes. Release bar 39 seen in Figs. 1 and 2 has a cam 39'' which extends to a point close to a further cam 28' on a pawl 28 and the bent end 40' of a lever 40 which is mechanically connected to stop-pawl 41 of ratchet 27 (Fig. 2). Moreover both release bars 39 are each fitted with a cam 39', which can operate a common release bar 36a for all stop-pawls 11 of the number rollers, as is particularly well shown in Fig. 1. This release bar works in conjunction with cams 11' attached to stop-pawls 11. Reversal hoop 37 is fitted with extensions 37' which work in conjunction with a comb-shaped reversal member 42 screwed on the inner surface of side-plates 1. This reversal member contains reversal points 42' which come into contact with the heart-shaped lugs 9 of number rollers 6 for reversing

the latter. Reversal hoop 37 also has a lug 37'' which works in conjunction with a lug 43, likewise heart-shaped, which is rigidly fixed on control wheel shaft 26 and serves to reverse control wheels 22 (Figs. 3-5). When it is required that reversal should be effected by hand, the reversal hoop is also fitted with a stop 37a, which is under the influence of press-button 44a of a press-key 44 fastened to one of the side-plates 1, which key is held when at rest by a spring 5. When automatic reversal is required the reversal hoop 37 is fitted with a special arm 37b which is connected by means of a strap 46 with the armature 45 of an electromagnet 47 serving as reversal magnet. The latter lies next to the other magnets 16 and 32. The general structure of the arrangement described is such that its components can be constructed uniformly, quite independent of whether the reversal takes place by hand or automatically. It can be fitted, according to requirements, with key 44 or with reversal magnet 47 or, if necessary, with both organs together. The first number roller 6 is fitted with a cam 6a which operates a working contact 49 by means of a pin 48 (Fig. 2). A further working contact 50 is under the influence of a control wheel shaft 26 through the intermediary of a drive 51 and a pin 52. (Fig. 3). The purpose of these contacts is explained by means of Figs. 7 and 8.

Fig. 7 applies to the design with manual reversal and represents the switch-system of a telephone subscriber's station equipped with a number indicator as described. This comprises, as usual, a set of fittings (Ga) consisting of the telephone T, the microphone M and the induction coil Ind, including the number switch with the impulse contact *i* or short circuit contact *k*, respectively and the call circuit with condenser Ko and alarm Wk. The exciting coil of the transmission magnet 16 for the number rollers of the number indicator lies in a circuit which is sporadically interrupted by impulse contact *i* of the number switch, which circuit is produced by the working side of short-circuit contact *k* developed as an alternating circuit. The exciting coil of commutation magnet 32 lies in a circuit closed by working contact 49 controlled by the first number roller 6, which circuit is in turn produced by the passive side of short-circuit contact *k*. The hook commutator HU serves as usual to close the station loop *a*, *b* and to cut out call circuit Ko, Wk.

The switch system according to Fig. 8 differs from the preceding system in that reversal magnet 47 and contact 50 are added. The exciting coil of the former is connected, like that of commutation magnet 32 by means of a second contact HUII of the hook commutator with contact 49. The contact 50 lies parallel to the working side of hook contact HUI serving to close the loop circuit *a*, *b* and to switch off the call circuit.

The arrangement described functions as follows: As can be seen from Figs. 7 and 8, the station loop between terminals *a* and *b* is closed by taking up the receiver, i. e. by changing over hook commutation contact HU or HUI. Upon dialing the number disc contact *k* is changed over whereby transmission magnet 16 of the number indicator is operated and the talking appliance Ga of the station is short-circuited. Armature 15 in Fig. 1 is attracted and transmission hoop 13 is swung to the left with the assistance of strap 14. Hoop 13 takes with it all the pawls 10,

which is made possible by the longitudinal holes 18. As pin 21 lies in hollow 23 of control wheel 22, the one pawl 10 which can just be seen in Fig. 1 is engaged with the corresponding ratchet 8. Since the hollows 23 provided on the rim of the corresponding control wheels 22 are displaced in relation to pins 21 corresponding to the other pawls, corresponding guide hoops 19 are in raised positions. The other pawls 10 are therefore raised off the corresponding ratchets 8 and are put out of action. Upon releasing the number disc (dial) the circuit of transmission magnet 16 is sporadically interrupted by impulse contact 5. The armature sinks accordingly and takes with it the engaged pawl 10 via transmission hoop 13 and rod 12. This causes the first number roller 6 to take up a position corresponding to the originally dialed number, so that this number appears in the first window 4 after completion of the first series of impulses. Contact 49 (Fig. 7), which prepares the circuit of commutator magnet 32, is only closed after number roller 6 has turned by one division. As soon as the dial has returned to rest contact k is turned back and commutator magnet 32 is excited. Armature 31 is attracted and causes commutation bar 29 to swing over to the left (Fig. 4). Pawl 28 is raised and moves behind the next cog of ratchet 27. At the same time both bars 35 are raised. They take rod 36 with them which moves up against all pawls 10 and lifts these in such a way that pins 21 are removed from control wheels 22 or that pin which lies in hollow 23 of the first control wheel 22 is taken out. As soon as rod 36 has reached its highest position as dictated by the length of the guide holes in side-plates 1, springs 34 become tense. These allow commutation bar 29 to continue its movement until pawl 28 engages in the next cog of ratchet 27. On the dial being operated again in order to send out the next series of impulses corresponding to the next number, contact k again switches over (Fig. 7), whereby commutator magnet 32 is deprived of current. Sinking armature 31 brings commutation bar 39 back into its original position. Springs 34 are first relaxed. Pawl 28 which was carried along now causes ratchet 27 and with it all the control wheels 22 to turn by one division. These are turned so far that all the pins rest on the rim when commutation bars 33 or rod 36 again take up their original position owing to the release of springs 34. At the close of the revolution of control wheel shaft 26 hollow 23 of the second control wheel 22 moves below pin 21 of the second pawl 10, so that the latter, owing to the entry of the pin in hollow 23, can engage with control wheel 8 of the second number roller 6. When the dial is next released the commutator magnet again comes into action. The second pawl 10 however now operates whereby the second number roller can be stepped in accordance with the second number originally dialed. At the end of the second impulse series contact k arrives in the position shown (Fig. 7) and commutator magnet 32 is again supplied with current. The same movement is repeated. The second pawl 10 is raised by the corresponding ratchet 8 and the next engaged with the third ratchet or the third number roller, whereby the latter can be obtained upon dialing the third number. The same takes place in respect of the remaining digits, until the number of the desired subscriber has been fully dialed. It is thus possible for the subscriber who is calling up to check the

number dialed and, should this not be correct, to hang up again before the reply comes.

In the case of reversal by hand key 44 is pressed down in opposition to spring 5. Head 44a which comes into contact with stop 31a carries the latter with it so that reversal hoop 37 is swung over to the left (Fig. 4). Release bars 39 are now raised. Connecting rod 36 is shifted upwards as in the switching-over process and moves up against all the pawls. The last pawl engaged becomes inoperative and the corresponding pin 21 is lifted out of hollow 23 of the last control wheel. At the same time cam 39' of release bar 39, which can be seen in Fig. 2, comes into contact with cam 28' of pawl 28 and with the bent part 40' of lever 40 in connection with stop-pawl 41. Both pawls 28 and 41 are raised off ratchet 27. The cams 39' of bar 39 move against rod 36a being thereby also raised, and with the help of 20 the cams 41' removing stop-pawls 11 from ratchets 8. In this way rollers 6 and control wheels 22 become free. When rod 36 has reached its final position springs 38 stretching between hoop 37 and release bars 39 are taut. The hoop continues its movement and extensions 37' carry reversal comb 42 with them so that reversal points 42' come into contact with the heart-shaped lugs 9 of number rollers 6, whereby the number rollers are reversed in the ordinary way. As shown in 30 Figure 6, the ends of the points 42' are located substantially opposite the largest-diameter sections of the lugs 9, so that the reversal of the number rollers can be conveniently effected. At the same time stop 37' (Fig. 3) comes into contact with the heart-shaped lug 43 mounted rigidly on control wheel shaft 26 whereby the control wheels are likewise reversed. On key 44 being released hoop 37 and the parts shifted by the hoop come back to rest. The first pin 21 returns to hollow 23 of the first control wheel 22 and the apparatus is again ready for receiving the next number. Upon reversing the first number roller 6 contact 49 opens again, whereby commutator magnet 32 is cut out.

45 For automatic reversal the reversal magnet 47 is excited by means of hook commutation contact HUII which was turned back on hanging up the receiver. Reversal hoop 37 is swung round in the manner illustrated in Fig. 4. The reversal process takes place as already described. When control wheel shaft 26 has reached its original position contact 50 opens. This serves to keep reversal magnet 47 under current until the reversal is completed in spite of the fact that 55 hook contact HUI has been turned back.

The number of rollers 6 depends on the operating conditions. In Switzerland, for example, subscribers' telephone numbers consist at the most of nine digits, of which three are intended 60 for the dialing of the region in the automatic trunk service, whereas the other six form the numbers of the subscribers' themselves. It is advisable to divide the capacity of the number rollers into eleven spaces, of which ten receive the digits 1 to 0 and the eleventh remains empty. When the number indicator is at rest the empty spaces appear through windows 4. In this way mistakes can be avoided with the greatest certainty when numbers are dialed which comprise less than the maximum number of digits. The electromagnets 16, 32, and 47 require only slight current since each operates separately. Moreover, the total energy stored in the air gap of the electromagnets is a function of the product of 65 the flux density squared by the distance of the

armatures from the magnetic poles by the pole area divided by 8π . Since the flux density is dependent upon the ampere turns and core material by increasing the ampere turns sufficient power has been developed to operate this mechanism of few moving parts. In addition, by keeping the air gap between the poles and the armatures to a minimum, the maximum efficiency of the electromagnets has been utilized.

I claim:

1. A number indicator for trunk call stations operating with automatic dials and having a number switch having a short circuit contact, said indicator comprising a plurality of number rollers, a separate ratchet rotatable along with each number roller, a separate pawl adapted to engage each ratchet, a transmission electromagnet, means connected with said transmission electromagnet for supplying a dialing current thereto to energize the same, means connected with said pawls and actuated by said transmission electromagnet to raise some of said pawls off said ratchets, a commutator electromagnet, a circuit connected with said commutator electromagnet, means connected with said circuit and the short-circuit contact of the number switch to energize said circuit in each case at the end of a series of impulses and to cause the switching over of the driving current from one number roller to the next, a separate control wheel for each pawl, means connecting said control wheels with said pawls, means connected with said control wheels and actuated by said commutator magnet for raising the pawls allotted to number rollers not to be dialed and bringing the pawl allotted to the number roller to be dialed into mesh with its ratchet, and means connected with said control wheels for actuating said pawls.

2. A number indicator for trunk call stations operating with automatic dials, said indicator comprising a plurality of number rollers, a separate ratchet rotatable along with each number roller, a separate pawl adapted to engage each ratchet, a transmission electromagnet, means connected with said transmission electromagnet for supplying a dialing current thereto to energize the same, means connected with said pawls and actuated by said transmission electromagnet to raise some of said pawls off said ratchets, a commutator electromagnet, a circuit connected with said commutator electromagnet, means connected with said circuit for interrupting the same when the indicator is at rest after the actuation of the first number roller, means connected with the exciting coil of said commutator electromagnet for transmitting current from said circuit thereto only after said first number roller has turned by at least one division, a separate control wheel for each pawl, means connecting said control wheels with said pawls, means connected with said control wheels and actuated by said commutator magnet for raising the pawls allotted to number rollers not to be dialed and bringing the pawl allotted to the number roller to be dialed into mesh with its ratchet, and means connected with said control wheels for actuating said pawls.

3. A number indicator for trunk call stations operating with automatic dials, said indicator comprising a plurality of number rollers, a separate ratchet rotatable along with each number roller, a separate pawl adapted to energize each ratchet, a transmission electromagnet, means connected with said transmission electromagnet for supplying a dialing current thereto to energize the same, means connected with said pawls

and actuated by said transmission electromagnet to raise some of said pawls off said ratchets, a commutator electromagnet, means energizing said commutator electromagnet after the energization of said transmission electromagnet and after each subsequent dialing, a separate control wheel for each pawl, means connecting said control wheels with said pawls, means connected with said control wheels and actuated by said commutator magnet for raising the pawls allotted to number rollers not to be dialed and bringing the pawl allotted to the number roller to be dialed into mesh with its ratchet, means connected with said control wheels for actuating said pawls one after the other, whereby said number rollers assume positions after each dialing in which the numbers dialed can be read thereon, a backward key, and means connecting said backward key with said number rollers and control wheels for reversing the same.

4. A number indicator for trunk call stations operating with automatic dials and having a receiver, said indicator comprising a plurality of number rollers, a separate ratchet rotatable along with each number roller, a separate pawl adapted to engage each ratchet, a transmission electromagnet, means connected with said transmission electromagnet for supplying a dialing current thereto to energize the same, means connected with said pawls and actuated by said transmission electromagnet to raise some of said pawls off said ratchets, a commutator electromagnet, means energizing said commutator electromagnet after the energization of said transmission electromagnet and after each subsequent dialing, a separate control wheel for each pawl, means connecting said control wheels with said pawls, means connected with said control wheels and actuated by said commutator magnet for raising the pawls allotted to number rollers not to be dialed and bringing the pawl allotted to the number roller to be dialed into mesh with its ratchet, means connected with said control wheels for actuating said pawls one after the other, whereby said number rollers assume positions after each dialing in which the numbers dialed can be read thereon, and means connected with said number rollers and control wheels for automatically reversing the same upon the hanging up of the receiver.

5. A number indicator for trunk call stations operating with automatic dials and having a receiver, and a hook commutator for said receiver, said indicator comprising a plurality of number rollers, a separate ratchet rotatable along with each number roller, a separate pawl adapted to engage each ratchet, a transmission electromagnet, means connected with said transmission electromagnet for supplying a dialing current thereto to energize the same, means connected with said pawls and actuated by said transmission electromagnet to raise some of said pawls off said ratchets, a commutator electromagnet, means energizing said commutator electromagnet after the energization of said transmission electromagnet, and after each subsequent dialing, a separate control wheel for each pawl, means connecting said control wheels with said pawls, means connected with said control wheels and actuated by said commutator magnet for raising the pawls allotted to number rollers not to be dialed and bringing the pawl allotted to the number roller to be dialed into mesh with its ratchet, means connected with said control wheels and actuating said pawls one after the other, whereby

said number rollers assume positions after each dialing in which the numbers dialed can be read thereon, a reversal magnet, means connecting said number rollers and control wheels with said reversal magnet, and means connecting the exciting coil of said reversal magnet with said hook commutator, whereby said number rollers and said control wheels are automatically reversed.

6. A number indicator for trunk call stations operating with automatic dials and having a receiver and a hook commutator for said receiver, said indicator comprising a plurality of number rollers, a separate ratchet rotatable along with each number roller, a separate pawl adapted to engage each ratchet, a transmission electromagnet, means connected with said transmission electromagnet for supplying a dialing current thereto to energize the same, means connected with said pawls and actuated by said transmission electromagnet to raise some of said pawls off said ratchets, a commutator electromagnet, means energizing said commutator electromagnet after the energization of said transmission electromagnet, and after each subsequent dialing, a separate control wheel for each pawl, means connecting said control wheels with said pawls, means connected with said control wheels and actuated by said commutator magnet for raising the pawls allotted to number rollers not to be dialed and bringing the pawl allotted to the number roller to be dialed into mesh with its ratchet, means connected with said control wheels for actuating said pawls one after the other, whereby said number rollers assume positions after each dialing in which the numbers dialed can be read thereon, a reversal magnet having a loop circuit, and a working contact dependent on the control wheels running parallel to the working side of said hook commutator and maintaining said loop circuit until the reversal of the number rollers and control wheels is completed.

7. A number indicator for trunk call stations operating with automatic dials, said indicator comprising a plurality of number rollers, a separate ratchet rotatable along with each number roller, a separate pawl adapted to engage each ratchet, a transmission electromagnet of suffi-

cient ampere turns to be operated by system current, means connected with said transmission electromagnet for supplying a dialing current thereto to energize the same, means connected with said pawls and actuated by said transmission electromagnet to raise some of said pawls off said ratchets, a commutator electromagnet of sufficient ampere turns to be operated by system current, means energizing said commutator electromagnet after the energization of said transmission electromagnet and after each subsequent dialing, a separate control wheel for each pawl, means connecting said control wheels with said pawls, means connected with said control wheels and actuated by said commutator magnet for raising the pawls allotted to number rollers not to be dialed and bringing the pawl allotted to the number roller to be dialed into mesh with its ratchet, means connected with said control wheels for actuating said pawls one after the other, whereby said number rollers assume positions after each dialing in which the dialed numbers can be read thereon, said number indicator further comprising a reversal magnet of sufficient ampere turns to be operated by system current, said reversal magnet having a loop circuit and a working contact dependent on the control wheels running parallel to the working side of said hook commutator and maintaining said loop circuit until the reversal of the number rollers and control wheels is completed.
